E. L. GARDNER.
WINDING DRUM.
APPLICATION FILED JAN. 4, 1922.

1,435,461.

Patented Nov. 14, 1922.

UNITED STATES PATENT OFFICE.

EDGAR L. GARDNER, OF ROCHESTER, NEW YORK, ASSIGNOR TO PULLMAN MFG. COMPANY, OF ROCHESTER, NEW YORK, A CORPORATION OF NEW YORK.

WINDING DRUM.

Application filed January 4, 1922. Serial No. 526,988.

To all whom it may concern:

Be it known that I, EDGAR L. GARDNER, a citizen of the United States, residing at Rochester, in the county of Monroe and State of New York, have invented certain new and useful Improvements in Winding Drums; and I do hereby declare the following to be a full, clear, and exact description of the same, reference being had to the accompanying drawings, forming a part of this specification, and to the reference numerals marked thereon.

My present invention relates to winding and reeling, and more particularly, to the construction of spring actuated winding devices such as are used for winding the cords or tapes of sash balances and the balancing devices of folding beds, and the invention has for its object to provide a simple, yet strong and efficient mode of construction for winding devices of this kind applicable to these and analogous uses, the improvements being directed in part toward facilitating the assembling of the device in the first instance. To these and other ends the invention consists in certain improvements and combinations of parts, all as will be hereinafter more fully described, the novel features being pointed out in the claims at the end of the specification.

In the drawings:

Figure 1 is a central section of a winding device constructed in accordance with and illustrating one embodiment of my invention;

Figure 2 is a front view thereof;

Figure 3 is a section on the line 3—3 of Figure 1;

Figure 4 is a perspective view of one of the housing parts hereinafter termed the yoke;

Figure 5 is a perspective view of another housing part hereinafter termed the shell;

Figure 6 is a side view of the device completely assembled with the exception of the cover plate which is about to be shoved in place;

Figure 7 is an enlarged detail of the axial part shown in Figure 3;

Figure 8 is a front view of the attaching eye for the tape, and

Figure 9 is an enlarged section on the line 9—9 of Figure 8.

Similar reference numerals throughout the several views indicate the same parts.

Although my invention, as hitherto suggested, is applicable to various uses, we will assume for the purposes of the present description that it is to be used as a sash balance. Referring more particularly to the drawings, the device comprises essentially a two part casing for the moving part consisting of a shell 1 that is set into the window frame or other support and attached in the manner hereinafter described. The shell is preferably of the form shown in Figure 5 and provides at 2 one of two opposed walls of the complete casing. Suitably secured centrally in this wall as by the riveted lugs 3 (Figure 7) is a split tube 4 forming a hub. In the method of assembly there is first inserted in this shell a cylindrical drum 5 having a single head 6 and an open side that is applied against the closed side 2 of the shell. The head 6 is provided with a central bore formed by striking up a collar 7 from the sheet material of which the drum is preferably made and this collar receives a bearing in the end of the hub 4, as shown in Figure 7. To reinforce this bearing connection I 80 swage into this collar 7 an annular reinforcing member or washer 8.

After the drum 5 is thus put in place I apply to the shell 1 a sheet metal yoke 9 that embraces the shell and the connecting portion 10 of which closes the open end thereof shown in Figure 5 while one of the side plates 11 which for convenience I have termed a bearing plate, partially closes the open side of the shell and provides a wall 12 opposite the wall 2. Both of the plates of the yoke are perforated as at 12 and a fastener 13 is next applied to extend through the yoke, the reinforcing member 8 and collar 7, the hub 4 and the wall 2 of the shell holding all of these parts together. This fastener may be in the form of a bolt or rivet as shown and it constitutes a spindle upon which the reinforcing member 8 of the drum 5 turns in addition to its bearing through the collar 7 within the hub member 4.

The drum 5 is spring actuated through the provision of a winding spiral spring 14 contained therein in the manner of an ordinary clock spring, the inner end being hooked

over the split in the hub 4 and the outer end being suitably attached at 15 to the periphery of the drum, as shown in Figure 1. The sash cord or tape 16 usually of thin metal is wound upon the exterior of the drum 5, and the end passes out through an opening 17 in the front or connecting portion 10 of the yoke 9, which opening is slotted to the edge of the yoke with diverging walls that converge upwardly and guide the tape onto the drum. As the tape is drawn out through the lowering of a window or otherwise, it moves against the opposition of the spring 14 which is thus energized and takes up the tape when the latter is released as by raising a window.

Of course the spring 14 must always be under some tension even when the tape is wound upon the drum to the fullest extent, and in making balances for folding beds, for instance, where a very strong spring is required, difficulty has hitherto been experienced in putting the spring drum under tension while assembling the casing about it.

With the present invention when the device is assembled as so far described, the drum 5 is partially closed due to the fact that the bearing plate 11 of the yoke only partially covers the open side of the shell 1 and the drum may be wound and conveniently clamped against movement by pressing with a suitable device against the head 6 of the drum and the opposite side of the shell, all of which is necessitated during the attachment of the tape 16. After the tape has been applied and reeled in as far as an eye or enlargement 18 on its free end will permit the clamp may be removed and the housing of the drum completed.

This last step is accomplished through the provision of a flanged cover plate 19 having a slot 20 extending through its center. I slide this plate into place beneath the bearing plate 11 of the yoke and between it and the head 6 of the drum until its square edge abuts the connecting portion 10 of the yoke whereby, because of the slot 20, the cover plate straddles the fastener 13 and completely closes the remaining portion of the open side of the shell. The shell, the plates of the yoke and the cover plate 19 are respectively provided with registering apertures 21, 22 and 23 that come into alinement when the parts are assembled and form an opening through the entire device through which a spike or bolt may be driven to hold the winding device in place on its support, and which securing means at the same time holds the structure together.

The enlargement forming an eye or attaching means 18 at the free end of the tape 16 to connect the latter to the window sash or other moving part is preferably of the form shown in Figures 8 and 9 wherein a slot 24 in the shank of the eye divides it into

two bars 25 and 26. The simple means of attaching the tape of pliable metal is to pass it around the bar 26, and then between the bar and in a reverse direction around bar 25, as shown in detail in Figure 9, the tip end being flattened down and requiring no further fastening.

I claim as my invention:

1. In a winding drum, the combination with a two part casing embodying opposed walls and a hub secured in one of said walls, of a spring drum arranged to turn between the walls and having a sheet metal head provided with an inwardly projecting collar struck from the material thereof, said collar having a bearing in the end of the hub, and a reinforcing member swaged into the interior of the collar. 75

2. In a winding drum, the combination with a two part casing embodying opposed walls and a hub secured in one of said walls, of a spring drum arranged to turn between the walls and having a sheet metal head provided with an inwardly projecting collar struck from the material thereof, said collar having a bearing in the end of the hub, an annular reinforcing member swaged into the interior of the collar and a spindle connecting the walls and extending through the hub, collar and reinforcing member and 95 furnishing a bearing for the latter. 85

3. In a winding drum, the combination with a casing embodying a shell having an open side and a closed side and a spring drum journaled in the shell, of a bearing plate partially covering the open side of the shell, a fastener extending through the said plate, shell and drum and a cover plate cooperating with the bearing plate to completely house the drum within the shell plate, and adapted to be applied last after the other parts have been assembled. 100

4. In a winding drum, the combination with a casing, embodying a shell having an open side and a closed side and a spring drum journaled in the shell, of a bearing plate partially covering the open side of the shell, a fastener extending through the said plate, shell and drum and a cover plate cooperating with the bearing plate to completely house the drum within the shell plate, said cover plate being slotted to slidably straddle the fastener and adapted to be applied last after the other parts have been assembled. 110

5. In a winding drum, the combination with a casing embodying a shell having an open side and a closed side and a spring drum journaled in the shell, of a bearing plate partially covering the open side of the shell, a fastener extending through the said plate, shell and drum and a cover plate cooperating with the bearing plate to completely house the drum within the shell plate, and adapted to be applied last after 115 123 130

the other parts have been assembled, the shell, bearing plate and cover plate being further provided with registering apertures to receive a securing device locking them together and by means of which the structure may be mounted upon a support.

6. In a winding drum, the combination with a casing embodying a shell having an open side and a closed side and a spring 10 drum journaled in the shell, of a yoke embracing the shell and embodying a bearing plate partially covering the open side of the shell, a fastener extending through the yoke, shell and drum, and a cover plate cooperat- 15 ing with the bearing plate to completely

house the drum within the shell plate and adapted to be applied last after the other parts have been assembled.

7. In a winding drum, the combination with a casing embodying a shell and a spring 20 drum journaled therein, of a yoke embracing the shell and having an opening in the connecting portion thereof, said opening having diverging lateral walls extending to one end of the yoke, a fastener extending 25 through the shell, drum and yoke, and a tape wound on the drum to pass out through the opening and along between the diverging walls and in the plane thereof.

EDGAR L. GARDNER.
